UNITED STATES PATENT OFFICE.

JAMES S. GRAVES, OF WASHINGTON, DISTRICT OF COLUMBIA.

DESIGN FOR A NECKTIE-HOLDER.

SPECIFICATION forming part of Design No. 32,356, dated March 20, 1900.

Application filed January 26, 1900. Serial No. 2,923. Term of patent 14 years.

To all whom it may concern:

Be it known that I, JAMES S. GRAVES, a citizen of the United States, residing at No. 612 G street northwest, Washington, District of Columbia, have invented and produced a new and original Design for a Necktie-Holder; and I do declare the following to be a full, clear, and exact description of the same, reference being had to the accompanying drawings, forming a part thereof.

As shown in the drawings, the leading or material feature of my design consists of a plate oval at each end and having a piece cut out of its upper end, leaving an opening which is oval at its upper end and narrowing to a point at its lower end, the plate having a V-shaped incision about its center and having one of its sides about one-fifth of its length checkered, forming teeth. The said sheet is bent substantially in the form of a compressed S.

My necktie-holder may be described as follows:

1 is the body, which is about six times longer than it is wide. The upper end turns out and then down a short distance, forming 30 a double U-shaped bend 2. The lower end turns back and then up a short distance, forming substantially another U-shaped bend 3, its upper end, however, resting against the rear face of the plate and its inner edge being 35 beveled at the point 6. On the inner face of the rear arm of this U-shaped bend are teeth 4. About midway the body of the holder is a V-shaped incision, and projecting from the face thereof is a point 5.

Having described my invention, what I claim as new, and desire to secure by Letters Patent, is—

The design for a necktie-holder, as shown and described.

In testimony whereof I affix my signature in presence of two witnesses.

JAMES S. GRAVES.
